UNITED STATES PATENT OFFICE

BENJAMIN H. BRITT, OF NEW YORK, N. Y., ASSIGNOR TO INTERNATIONAL MOTOR COMPANY, OF NEW YORK, N. Y., A CORPORATION OF DELAWARE

COOLING SYSTEM

Application filed August 14, 1928. Serial No. 299,510.

The present invention relates to cooling systems for motor vehicles and embodies an improved construction which provides greater cooling than is possible with cooling systems of the present type.

In motor vehicle construction the problem of providing an adequate radiating surface for the cooling system of the engine imposes a serious limitation upon the conventional design. Existing practice has mounted the radiator at the front of the vehicle and utilized an engine driven fan to induce a sufficient flow of cooling air through the radiator. It is quite apparent that the limitations upon constructions of this kind are considerable, and being unable to increase the size of the radiator, the quantity of air drawn therethrough has been increased.

With increased demands upon individual units, it has been found that the above limitations present a serious factor in motor vehicle design and the present invention has for an object the provision of a cooling system, the physical limitations of the space occupied thereby being practically removed.

A further object of the invention is to provide an improved radiator construction having a fan or fans to induce a flow of cooling medium through the radiator regardless of whether the vehicle is moving or at a standstill.

It is a further object of the invention to provide a radiator construction of the above character in which cooling fans are provided to rotate in opposite directions, depending upon the direction of travel of the vehicle.

Further objects will be apparent as the description proceeds and reference will now be had to the accompanying drawing, wherein:

Figure 1 is a plan view, partly broken away, showing a preferred form of the invention wherein the radiator is mounted upon the top of the vehicle and at the rear thereof.

Figure 2 is a side view, showing the radiator construction of Figure 1.

Figure 3 is an end view of the radiator shown in Figures 1 and 2.

Figure 4 is a wiring diagram showing the manner in which the fans are connected so

that their direction of rotation will be reversed upon a reversal of the direction of travel of the vehicle.

Referring to the above drawings, *a* designates a vehicle body, the top of which is provided with a radiator *b* vertically mounted at the rear. This radiator may be formed with a plurality of sections, in the present instance two being shown, and each section is provided with a filling spout *b'*. Rearwardly of the radiator sections, and mounted upon the top, a plurality of fan motors *c* are provided. These motors drive fans *c'* which induce a flow of air through the radiators.

A suitable hood *d* is mounted over the fans, the hood being formed with hinged door members *d'* having louvers *d''* for directing the flow of the cooling medium. Rearwardly of the hood, a transverse door *e* is provided to restrict the flow of air to the radiators.

The fans are connected for reverse rotation in accordance with the direction of travel of the vehicle and Figure 4 illustrates, diagrammatically, a suitable connection for the motors. Control switch *f*, which controls the movement of the vehicle, is provided with field contacts *f'* for reversing the fields of the motors upon movement of the switch in either direction. Battery *g* is connected to the movable contacts *f''* of the switch and also to the armatures *h* of the fan motors. The motor fields *h'* are connected to the contacts *f'* and the circuit through the armatures and battery is completed through contacts *f''*. It will be seen that movement of the switch *f* into either direction will cause the fans to be rotated in a corresponding direction in accordance with the movement of the vehicle.

It will be seen that the available space for mounting radiators is practically unlimited and adequate cooling may be provided by a suitable design of cooling unit. While the invention has been described in connection with the accompanying drawings, it is not to be limited, save as defined in the appended claims.

I claim as my invention:

1. A cooling system for a vehicle having a control for reversing the movement thereof, comprising a radiator, means for mounting

- the radiator upon the roof of the vehicle, a hood associated with the radiator, means within the hood for creating a flow of cooling air therethrough, and means to reverse the direction of the flow creating means when the direction of movement of the vehicle is changed.
2. A cooling system for a vehicle having a control for reversing the movement thereof, comprising a radiator, means for mounting the radiator upon the roof of the vehicle at the rear thereof, a hood associated with the radiator, a door at the end of the hood to restrict the flow of air therethrough, means within the hood for creating a flow of cooling air therethrough, and means to reverse the direction of the flow creating means when the direction of movement of the vehicle is changed.
3. A cooling system for a vehicle having a control for reversing the movement thereof, comprising a radiator, means for mounting the radiator upon the roof of the vehicle at the rear thereof, a hood associated with the radiator, a door at the end of the hood to restrict the flow of air therethrough, a fan within the hood for creating a flow of cooling air therethrough, and means to reverse the direction of rotation of the fan when the direction of movement of the vehicle is changed.

This specification signed this 8th day of August, A. D. 1928.
